United States Patent Office.

FRANCIS E. MILLS, OF SAN FRANCISCO, CALIFORNIA.

Letters Patent No. 64,894, dated May 21, 1867.

DOOR INDICATOR.

The Schedule referred to in these Letters Patent and making part of the same.

TO ALL WHOM IT MAY CONCERN:

Be it known that I, FRANCIS E. MILLS, of the city and county of San Francisco, and State of California, have invented a new and improved Door Indicator to be inserted in the street doors of offices, combined with a note-box for the reception of letters, cards, and notes; and I do hereby declare that the following is a full, clear, and exact description thereof, which will enable others skilled in the art to make and use the same, reference being had to the accompanying drawings, forming part of this specification.

The nature of my invention consists, first, in cutting an aperture through the body of the door, covered with a glass face in front, through which any written or printed announcement made opposite the glass on the inside may be seen from without; second, adapting to fit the recess formed behind this glass face, a mechanical device combined with words and figures by means of which the occupant may easily and quickly indicate his presence, engagement, or absence, and the duration of such absence, or make any other announcement desired, without liability to change, disturbance, obliteration, or destruction by persons outside; and, third, combining in the same plate which mounts the indicator on the outside of the door an aperture for the reception of cards, letters, notes, &c.

The object of this invention is first to enable the lady of a house to avoid the waste of time, interruption of business, and annoyance occasioned by the frequent ringing of the door-bell during that portion of the day required for her own laborious avocations; second, when really absent it enables the occupant, (particularly a professional man,) to inform all persons who may call on business, when and where he may be found, enabling them at the same time to leave any information, orders, appointments, &c., through the note-box; it also permits letter-postmen, collectors, &c., to deposit their letters or bills without the delay and annoyance incident to ringing the bell; the whole constituting a neat, convenient, cheap, and safe medium of communication both ways. In the accompanying plate of drawings my improvements are illustrated—

Figure 1 being a front view of the same.

Figure 2, a vertical section taken in the plane of the line $z z$, fig. 1; and

Figure 3, a detail view.

Similar letters of reference indicate like parts.

A, a circular plate made of silver or other metal, of about three-quarters of an inch in diameter, with a circular opening, B, cut out in its centre of about one and three-quarters of an inch diameter. Between this opening B and the periphery of the plate is cut another narrow opening or slot D, semicircular in form, about three-sixteenths of an inch wide, and extending in length nearly half way around the circle. The first or circular opening is to form the face of the indicator, and the semicircular slot, D is to form the face of the aperture for the reception of letters and cards. This flat plate, thus prepared, is placed on the front side of the door at the proper height, and after carefully marking out the position of the two apertures on the wood, two corresponding holes or openings are cut entirely through the door, using for the circular opening an auger-bit of same size as the circle to be cut out, and for the semicircular slot a small compass-saw. A piece of clear plate glass of circular form, a trifle larger than the circular hole in the door, is then taken and set in front of the circular hole, sinking its thickness in the wood, so that the outside surface of the glass shall be flush with the face of the door. I then replace the silver plate on the face of the door, the two openings in the plate being exactly against and corresponding with the two openings in the door, and fasten it permanently in that position with screws or otherwise. This completes the outside face of both the note-box and the indicator, and forms a cylindrical recess C on the inside of the door, with a glass face through which any words or figures presented toward that face on the inside may be seen from the outside. I then construct a cylindrical box, b, with a cap or cover, c, similar in form and structure to the ordinary pill-box used by druggists and apothecaries, except that the sides of the box project slightly beyond the flat bottom in the end opposite the cover, forming a shallow sink in that end of the box. The diameter of this box is such as just to permit it to be slipped into the recess r behind the glass on the inside of the door, and its length about one-third of an inch greater than the thickness of the door. This box or cylinder may be made of wood, metal, papier-mâché, or any other material convenient and suitable. On the flat end of the box forming the cover I stamp or print permanently the word "OUT" in large letters, and immediately below this the word "TILL" in smaller letters, and below this, again, I cut a hole, h, entirely through the flat cover near the rim, about one-quarter of an inch square, through which any figure could be

seen which might stand immediately opposite such hole inside the cover. I then fit a flat circular plate of metal, wood, or pasteboard, about one-eighth of an inch thick, in the inside of the cover close against the flat top, but not so tight but that it may be turned freely inside the rim. On that side of this plate next the hole *h*, I print an hour circle of figures representing the hours of the day, as shown at *d*, the figures being in such a position that when the plate is revolved inside the cover, each figure, from "1" to "12" inclusive, is brought in succession directly opposite this hole *h*, so that if this dial-plate should be turned inside the cover till the figure "4" be brought opposite the hole, the reading on the end of the box would be "OUT TILL 5," and so for any other figure desired.

The device for revolving the dial-plate *P* with the box closed is the following: In the open end of the box which the cover slips over, I cut out two gains *ff* opposite each other, about one-eighth of an inch deep, and to match these gains I raise on that side of the dial-plate opposite the dial two corresponding projections *ii*, so that when the box is closed these gains *ff* clutch the projections *ii* on the dial-plate, and cause it to revolve as the box is turned within the cover. The effect of this arrangement is that when the occupant wishes to indicate that he is "OUT" till a certain hour of the day, he has only to take the cylinder from its place in the recess, turn the cap with the thumb and fingers till the desired figure presents itself opposite the hole *h*, then replace it in the recess with that end toward the glass, and the reading is seen from without. This cap end of the cylinder when presented toward the glass simply represents that the occupant is "OUT" till a stated hour, and the other end is left blank to be presented toward the glass whenever the occupant of the house or room wishes to be considered "IN." But as it may be desired in some cases to indicate "engaged," or engaged to a certain party, or to state the place of absence, or some other special fact not possible to announce on the single fixed disk, I have made the cylinder in the form of a hollow box for the purpose of containing a number of separate circular cards or disks, some of them left blank, and made of ivory for convenience of erasing, to be filled up by the occupant with such special announcements as he may have occasion to make. These special cards *SS* are made to fit the shallow sink *t* formed in the reverse end of the cylinder, and whenever a special announcement is required, the card containing such announcement is taken from the box, slipped into the sink *t* on the reverse end of the cylinder, and that end presented toward the glass face. Whenever it should be desired, a lock-box can be attached to the door inside by a hinge on its lower edge. The box could be made to cover both the letter, slot, and the indicator and lock against the door on the upper edge.

I do not claim as my invention any of the paper devices made to hang up or fasten against the outside of a door for the purpose of indicating the absence and period of return of the occupant, for such indicators are already known and in use; but what I do claim as my invention, and desire to secure by Letters Patent, is—

1. The reversible box *b*, provided with the lettered cover *c*, having the hole *h* and the revolving disk *P*, said box containing a series of lettered or blank disks *SS*, adapted to be placed in the sink *t* in the reverse end in the said box, substantially as described for the purpose specified.

2. The reversible box *b*, in combination with the door, glass plate, circular plate *A*, having circular opening *B*, and semicircular opening *D*, substantially as described for the purpose specified.

FRANCIS E. MILLS.
